CAKE PAN HOLDER

Elizabeth E. Rohling, 4114 Irving Ave. N.,
Minneapolis, Minn. 55412

Filed Mar. 25, 1968, Ser. No. 11,112

Term of patent 3½ years

Int. Cl. D7—99

U.S. Cl. D44—10

FIG. 1 is a perspective view of a cake pan holder showing my new design, with a cake pan shown in broken lines for illustrative purposes only;

FIG. 2 is an elevational view;

FIG. 3 is a top plan view; and

FIG. 4 is a bottom plan view.

I claim:

The ornamental design for a cake pan holder, as shown and described.
